UNITED STATES PATENT OFFICE

ARTHUR C. RUNGE AND ERNEST C. BADGER, OF DETROIT, MICHIGAN; SAID BADGER
ASSIGNOR TO SAID RUNGE

FUEL-CHARGE MOISTENER

Application filed January 5, 1929. Serial No. 339,472.

This invention relates to fuel charge moisteners for internal combustion engines and the object of the invention is to provide a device for automatically adding moist air 5 to the fuel charge of an internal combustion engine while the engine is in operation.

A further object of the invention is to provide a device in which the moist air inlet is automatically closed when the engine stops 10 running and which will automatically open again after the engine is started.

A further object of the invention is to provide a device including a plunger movable longitudinally of a cylinder having a bypass 15 therein, the device being so balanced that during certain operating speeds of the engine the plunger floats in a position adjacent the bypass to allow the moisture carrying air to pass thereabout and at other speeds the 20 plunger automatically shuts off the moisture carrying air.

A further object of the invention is to provide a device of the character described 25 adapted to be connected into an automobile radiator at the inlet end above the water level therein, the outlet of the device being connected into the intake manifold of the internal combustion engine through which the fuel charge is drawn.

30 These objects and the several novel features of the invention are hereinafter more fully described and claimed and the preferred form of construction by which these objects are attained is shown in the accompanying drawings in which—

Fig. 1 is a view showing the connection of the device to an automobile radiator and an intake manifold.

Fig. 2 is an enlarged vertical section there- 40 through.

Fig. 3 is a section taken on line 3—3 of Fig. 2.

Fig. 4 is a detail section showing an alter- 45 native form of construction.

As shown in Figs. 2 and 3 the device com- 45 prises a casting 1 to which a hollow cylinder 2 is secured by the screws 3. This chamber 2 is provided with a pair of diametrically opposite enlarged portions or pockets 4 50 which provide a bypass about the plunger 5

when positioned therebetween. At the lower end the cylinder 2 is provided with a boss 6 having an opening 7 therethrough and a raised flange 8 is provided about the opening 7 within the cylinder 2 as shown. The lower end of the aperture 7 is internally threaded 55 to receive a pipe 9 shown in Fig. 1 which extends into the intake manifold 10 of the internal combustion engine. The casting 1 is provided with an angular inlet opening 11 leading into a recess 12 about the plunger stem 13. This plunger stem 13 is connected as shown in Fig. 2 to the plunger 5 which includes a circular plate 14 having a resilient face 15 secured thereto by the rivets 16. A disc 17 of resilient material is provided on the upper side of the plunger 14 and in the position shown in Fig. 2 this resilient disc 60 engages against the terminal flange 18 about the recess 12 and closes the said recess 65 preventing air from being drawn through the conduit 11.

This conduit 11 is connected by means of a pipe 19, shown in Figs. 1 and 3, to the top 70 of the radiator 20 above the water level there- 75 in as shown. The plunger stem 13, as shown in Figs. 2 and 3, is provided with a groove 21 and a set screw 22 engages in this groove and prevents rotative movement of the plunger and stem while allowing vertical 80 movement thereof. A spring pressed ball or other member 23 is positioned in the bottom of the recess 24 in the casting 1 and a spring 25 is provided adjustable by the set screw 26 to vary the pressure on the ball. 85 The plunger stem 13 is provided with a notch 27 in which this ball engages when the plunger is in the raised position as shown in Fig. 2. The object of the spring pressed ball 23 and notch 27 is to hold the plunger 90 in the closed position which prevents the moisture carrying air from entering manifold until the engine has attained a certain speed after starting. A similar ball 28 is provided in the recess 29 in the casting 1 and a spring 30 is provided adjustable by the screw 31 to vary the tension of the spring 95 on this ball.

As shown in Fig. 3 a notch 32 is cut in the stem 13 for the ball 28 as the ball will en- 100

gage in this notch as the stem moves downwardly through the casting 1. The object of this spring pressed member 28 and notch 32 is to help hold the plunger in the open position at certain operating speeds.

5 The upper end of the stem 13 is threaded and a coiled spring 33 is positioned thereabout and seats in the recess 34 formed in the casting 1. The upper end of the spring engages a washer 35 and a pair of lock nuts 36 are provided for adjusting the tension of the spring.

10 In Fig. 4 an alternative form of the device is shown. In this form the set screw 22 and the slot 21 in which it engages are left out so that the stem and plunger may rotate in the casting. In this form circumferential grooves 27^a and 32^a are provided in the stem 13 which are adapted to be engaged by the 15 spring pressed ball 23^a or other means.

15 In operation the suction from the intake manifold 10 is communicated through the pipe 9 to the cylinder 2 beneath the plunger 5. When the engine is cranked by hand 20 or turned over by the starting motor the suction produced in the intake manifold 10 tends to draw the plunger 5 downwardly. This motion is prevented by the spring 25 pressed ball 23^a and notch 27 until the engine has attained a certain speed. After the 30 engine starts and is idling a considerable suction is produced due to the air inlet for the carburetor being nearly closed, the first effect 35 of which will be to draw the plunger 5 downwardly to the bottom of the cylinder and into engagement with the flange 8 about the outlet 40 opening 7 thus closing off the outlet. However, when the engine speed is increased by opening the air inlet or throttle valve the suction is reduced and the spring 33 tends to raise the plunger.

45 The tension on the spring 33 may be so adjusted that the plunger 5 will be raised to a position between the enlarged portions 4 of the cylinder when the engine is running at certain operating speeds. The plunger is assisted to remain in this position by the spring pressed ball 28 engaging in the notch 32 or other means may be provided for this purpose. As 50 this plunger rises it reaches a point between the enlarged portions 4 of the cylinder, as shown in dotted lines in Fig. 2, at which time the air and vapor off the top of the radiator 55 20 is drawn through the pipe 19, conduit 11 and recess 12 and through the pockets 4 about the plunger and thence through the pipe 9 into the intake manifold of the engine.

60 This adds vapor to the fuel charge passing into the engine through the intake manifold 10 and the spring pressed ball 28 engages in the notch 32 in the plunger stem to yieldably hold the plunger in this position. As 65 soon as the engine stops the suction ceases and the spring 33 raises the stem so that

the plunger shuts off the air inlet by closing the bottom of the recess 12.

70 In the form shown in Fig. 4 only one ball is required which may engage in the groove 27^a when the plunger is in the raised position and will engage in the groove 32^a when the plunger is in the intermediate position.

75 In starting the engine it is necessary to draw a rich mixture of air and gasoline from the carburetor and for this reason it is necessary to shut off the auxiliary air supply through the fuel charge moistener and this is accomplished by providing the resilient disc 17 which shuts off air flow through the fuel charge moistener as long as the spring 33 and ball 23 engaging in the notch 27 holds the plunger in the raised position. This effectively prevents air flow through the fuel charge moistener during turning over of the engine for starting, but as soon as the engine starts and runs at idling speed the plunger is drawn downwardly to close the outlet and as the throttle is opened to increase the engine speed the suction is partially relieved allowing the plunger to rise to position between the bypasses 4 and allow flow of moist air thereabout into the intake manifold.

80 From the foregoing description it becomes evident that the device is very simple and efficient in operation, will not easily get out of order, will automatically add moisture to the fuel charge in the form of vapor and provides a device which accomplishes the objects described.

85 Having thus fully described our invention, its utility and mode of operation, what we 90 claim and desire to secure by Letters Patent of the United States is—

95 1. In a fuel charge moistener for an internal combustion engine having a water circulating radiator, a cylinder, an inlet for the cylinder connected to the radiator above the water level therein, an outlet for the cylinder opening into the intake manifold of the internal combustion engine, a plunger movable longitudinally of the cylinder to close the inlet or the outlet, a stem secured to the plunger and extending through the top of the cylinder, an adjusting nut threaded onto the end of the stem, a coiled spring about the stem adapted to be placed under tension by adjustment of the adjusting nut, a spring pressed member, means on the stem adapted to be engaged by the spring pressed member when the plunger is in position intermediate the inlet and outlet, a second spring pressed member, means on the stem adapted to be engaged by the second spring pressed member when the plunger is in position to close the inlet, and a bypass formed in the wall of the casing allowing flow of air about the plunger when in position intermediate the inlet and the outlet.

100 2. In a fuel charge moistener for an internal combustion engine having a water circulating radiator, a cylinder, an inlet connected

to the radiator above the water level therein and opening into the top of the cylinder, an outlet in the bottom of the cylinder opening into the intake manifold of the internal combustion engine, a plunger movable vertically in the cylinder between the inlet and the outlet, an adjustable spring normally holding the plunger in position to close the inlet, the cylinder being provided with a bypass in the 5 wall thereof intermediate the inlet and the outlet, the plunger being movable to position to close the inlet or the outlet, a stem secured to the plunger, a notch in the stem and yieldable means engaging the notch when the 10 plunger is opposite the bypass.

3. In a fuel charge moistener for an internal combustion engine having a water circulating radiator, a cylinder, an inlet connected to the radiator above the water level therein 20 and opening into the top of the cylinder, an outlet in the bottom of the chamber opening into the intake manifold of the internal combustion engine, a plunger movable vertically in the cylinder between the inlet and the outlet, an adjustable spring normally holding the plunger in raised position to close the inlet, the plunger being movable to position to close the outlet upon increase of suction in the 25 cylinder, and a bypass through which air may flow about the plunger when positioned 30 between the inlet and the outlet.

4. In a fuel charge moistener for an internal combustion engine including a water circulating radiator, a cylinder, an inlet in 35 the top of the cylinder, an outlet in the bottom of the cylinder, a plunger movable vertically in the cylinder between the inlet and the outlet, an adjustable spring normally holding the plunger in position to close the inlet, the cylinder 40 being provided with a bypass intermediate the inlet and the outlet, the outlet being connected to the intake manifold of the internal combustion engine and the inlet being connected into the radiator above the water 45 level therein.

5. In a fuel charge moistener for an internal combustion engine having a water circulating radiator, a cylinder, an inlet connected to the radiator above the water level 50 therein and opening into the cylinder, an outlet for the cylinder opening into the intake manifold of the internal combustion engine, a plunger movable in the cylinder to close the inlet or the outlet, an adjustable spring 55 normally holding the plunger in position to close the inlet, the cylinder being provided with a pair of diametrically opposite enlargements providing a bypass about the plunger when positioned therebetween.

60 6. In a fuel charge moistener, for internal combustion engines having a water circulating radiator, a chamber, an inlet open to the radiator above the water level therein and opening into the chamber, an outlet for the 65 chamber opening into the intake manifold

of the internal combustion engine, a plunger movable in the chamber to close the inlet or the outlet, an adjustable spring normally holding the plunger in position to close the inlet and a bypass between the inlet and the outlet adapted to be opened by the plunger when moved to position intermediate the inlet and the outlet.

In testimony whereof we sign this specification.

ARTHUR C. RUNGE.
ERNEST C. BADGER.
